UNITED STATES PATENT OFFICE.

FREDERICK GRINNELL, OF PROVIDENCE, RHODE ISLAND.

AUTOMATIC FIRE-EXTINGUISHER.

SPECIFICATION forming part of Letters Patent No. 269,201, dated December 19, 1882.

Application filed June 13, 1881. (No model.)

To all whom it may concern:

Be it known that I, FREDERICK GRINNELL, of the city and county of Providence, State of Rhode Island, have invented a new and useful Improvement in Automatic Fire-Extinguishers; and I hereby declare that the following is a full, clear, and exact description of the same, reference being had to the accompanying drawings, forming part of this specification.

This invention has reference to an improvement in the distributors of water of automatic fire-extinguishers; and it consists in providing a nipple or pipe with a cap secured by a solder composed of a material fusible at a low temperature, with a head having lateral openings, (from which the water is discharged,) and a deflector opposite each opening, so that the water discharged from each lateral opening will be deflected into fine spray and in all directions, as will be more fully set forth hereinafter.

Figure 1 is a view of my improved distributor, showing the deflectors secured by curved rods a short distance from the head. Fig. 2 is a sectional view, showing the seal secured within the nipple, the lateral outlets, and the deflectors placed close to the outlets. Fig. 3 is a top view of the device, showing four deflectors placed opposite four holes in the head.

In the drawings, *a* is a short piece of pipe provided on each end with a screw-thread, and known in the art as a "nipple." It is provided near its center with a six-sided wrench-bearing, so that it can be readily screwed into any kind of pipe-fitting.

b is a cap secured within the nipple *a* by a solder made of materials fusible at a low temperature, so that when the nipple is secured 40 to a system of pipes by which water is supplied to all parts of a building, and the temperature of the place where the nipple is secured is raised above the temperature at which the solder melts—say at from 120° to 160° 45 Fahrenheit—the melting of the solder will release the cap and the water will rush out of the pipe.

c is a head secured by a screw-thread to the nipple *a*. It is provided with two, three, or 50 more lateral outlets, *dd*, of such diameter that the area of them all combined is not more than

the area of the nipple, so that the pressure will be maintained and the water ejected with considerable force. *ee* are deflectors, made preferably in the form of a cone with the apex removed; but they may be made in any other form that will deflect the water in the desired direction, such as a plain, a concave, or a convex disk.

In automatic fire-extinguishers it is desirable to throw a portion of the water against the ceiling of the room in such a manner as to cover and protect a fixed area of the ceiling, and to throw the rest of the water equally over the largest area on the floor that can be thoroughly wetted down by each extinguisher. My present device may be constructed to throw the water into every portion of a room, so that such rooms—as a picker-room in a cotton-mill—may be thoroughly protected, and in 65 such a room the deflectors should be of such form that the water will be thrown with the best effect on the parts of the room most liable to be on fire, where a fire will burn most rapidly, or where the fire can most readily communicate with other parts of the building. By adapting the form, angles, or axes of the deflectors to the conditions, any room can be protected against fire, so that a disastrous fire will be an impossibility.

ff are the rods by which the deflectors are secured and held in place against the force of the impinging water. The deflectors may, however, be secured in any other convenient manner.

Having thus described my invention, I claim as new and desire to secure by Letters Patent—

1. An automatic fire-extinguisher provided with a seal secured by a solder fusible at a low temperature, a head provided with lateral outlets, and deflectors placed in front of each outlet, constructed to distribute the water, as described.

2. In an automatic fire-extinguisher, the combination, with the nipple *a* and seal *b*, of the head *c*, provided with lateral outlets *dd*, and the deflectors *ee*, constructed to deflect the water, as described.

FREDERICK GRINNELL.
